DESCRIPTION

FIG. 1 is a top left side perspective view of a sugar cane harvester base cutter knife of a first embodiment of the present design:

FIG. 2 is a top right side perspective view of the sugar cane harvester base cutter knife of FIG. 1;

FIG. 3 is a front view of the sugar cane harvester base cutter knife of FIG. 1;

FIG. 4 is a right side view of the sugar cane harvester base cutter knife of FIG. 1;

FIG. 5 is a top view of the sugar cane harvester base cutter knife of FIG. 1;

FIG. 6 is a back view of the sugar cane harvester base cutter knife of FIG. 1;

FIG. 7 is a left side view of the sugar cane harvester base cutter knife of FIG. 1;

FIG. 8 is a bottom view of the sugar cane harvester base cutter knife of FIG. 1;

FIG. 9 is a top front perspective view of a sugar cane harvester base cutter knife of a second embodiment of the present design;

FIG. 10 is a top back side perspective view of the sugar cane harvester base cutter knife of FIG. 9;

FIG. 11 is a left side view of the sugar cane harvester base cutter knife of FIG. 9;

FIG. 12 is a top view of the sugar cane harvester base cutter knife FIG. 9;

FIG. 13 is a back view of the sugar cane harvester base cutter knife of FIG. 9;

FIG. 14 is a left side view of the sugar cane harvester base cutter knife of FIG. 9;

FIG. 15 is a bottom view of the sugar cane harvester base cutter knife of FIG. 9;

FIG. 16 is a front view of the sugar cane harvester base cutter knife of FIG. 9;

FIG. 17 is a top left side perspective view of a sugar cane harvester base cutter knife of a third embodiment of the present design;

FIG. 18 is a top right side perspective view of the sugar cane harvester base cutter knife of FIG. 17;

FIG. 19 is a front view of the sugar cane harvester base cutter knife of FIG. 17;

FIG. 20 is a right side view of the sugar cane harvester base cutter knife of FIG. 17;

FIG. 21 is a top view of the sugar cane harvester base cutter knife of FIG. 17;

FIG. 22 is a back view of the sugar cane harvester base cutter knife of FIG. 17;

FIG. 23 is a left side view of the sugar cane harvester base cutter knife of FIG. 17; and,

FIG. 24 is a bottom view of the sugar cane harvester base cutter knife of FIG. 17.
